[57] CLAIM

The ornamental design for a children's light switch, as shown and described.

DESCRIPTION

FIG. 1 is a front elevational view of the children's light switch showing my new design;

FIG. 2 is a rear elevational view thereof;

FIG. 3 is a left side elevational view thereof;

FIG. 4 is a right side elevational view thereof. The broken line showing of the switch outlet box is included for the purpose of illustrating environmental elements only and forms no part of the claimed design;

FIG. 5 is a top plan view thereof; and,

FIG. 6 is a bottom plan view thereof.

FIG. 1

FIG. 2

FIG. 3

FIG. 4
